UNITED STATES PATENT OFFICE.

WILLIAM V. D. KELLEY, OF BROOKLYN, NEW YORK, ASSIGNOR TO PRIZMA,
INCORPORATED, A CORPORATION OF MAINE.

SENSITIVE PLATE, FILM, OR THE LIKE FOR COLOR PRINTS.

Application filed March 23, 1920. Serial No. 368,056.

To all whom it may concern:

Be it known that I, WILLIAM V. D. KELLEY, citizen of the United States, and resident of Brooklyn, in the county of Kings and State of New York, have invented certain new and useful Improvements in Sensitive Plates, Films, or the like for Color Prints, of which the following is a specification.

10 This invention relates to photographic material and has particular reference to the production of photographic material as an article of manufacture ready for the usual printing with negatives by the user.

15 The object of the invention is to simplify the procedure necessary to be followed by producers of colored pictures on plates, film or paper, and more particularly transparencies reproducing the colors of nature

20 on the additive principle by transmitted light.

At the present time, so far as I am aware, manufacturers of colored pictures are compelled to perform in their own plants practically all the special operations necessary to produce the pictures, as the manufacturers of sensitized paper, plates and films, only make up special materials of this character for manufacturers of colored pictures

25 upon order, which involves excessive expense to the purchaser, non-uniformity of material owing to the present relatively small consumption, and also delay in obtaining even ordinary material for color work owing

30 to the special care required in the manufacture of plate, film or paper, for color work uniformity required in different lots, like printing speeds of different emulsions, etc. At the present time there are no light sensitive media in the market specially prepared

35 for use in producing colored pictures, whereas if such partially prepared materials can be obtained there will immediately be a very wide extension of color photography owing

40 to simplification of the work to be done.

In my application 243,879, filed July 8, 1918, patented April 20, 1920, #1,337,775, is disclosed a process for producing colored pictures on the additive principle, and the

45 resulting colored picture product, which is peculiarly suitable for use by workers of ordinary skill, provided the precision work necessary in preparing the plate or film to receive the color value images is already performed. As will be seen upon reference

to said application and patent, the plate or film is first photographically printed with a finely subdivided pattern or design, leaving in the interstices of the emulsion residual sensitive portions which receive the impressions from the color value negative. A double coated plate or film is specifically shown having the design on one side in registry with the sensitive portion on the other, the finished plate or film being produced by coloring both the image and design on one side in one color and the image and design on the other side in another color, and additively producing complete color when the design is sufficiently fine. Exceedingly accurate work is required in making the design printing screens, and also in printing the design on the sensitized plate or film, and in accurately correlating the second design on the other side, and in the case of relatively narrow motion picture films for example, an unnecessary expense is involved in printing the strip, immediately before the negatives are printed.

It is the object of this invention to provide as an article of manufacture, design printed undeveloped sensitized plate or film to be made by the manufacturer in large quantities, and sold to the trade ready for printing from negatives. Thereby, the manufacturer of colored pictures is relieved of the necessity of having the necessary screens and doing his own design printing, but can obtain the desired design in printed stock, either single coated or double coated, from the manufacturer at low cost and with the assurance of greater uniformity.

This application is in part a continuation of said application 243,879 and patent aforesaid.

In the accompanying drawings:

Figure 1 shows a single coated photographic plate or film embodying the invention,

Figure 2 shows two transparencies placed together with the designs displaced, and

Figure 3 shows a double coated plate or film such as illustrated in Figure 1 of the aforesaid patent, embodying the invention.

Referring to Figure 1, 1 represents the base, either of transparent, translucent or opaque paper, glass, celluloid or the like, carrying an ordinary sensitive emulsion 2. This material is ordinarily made up in large sheets by the manufacturer, and in the case

of plates and papers, is cut to stock size and packed for the trade. In the case of films, the large sheets are slit along the dotted lines shown in dark rooms into strips then 5 perforated along the edges in the dark and packed for shipment. Heretofore it has been necessary for the user of these materials to provide his own screens, precision printing mechanism, etc., in sufficient quantity to 10 produce the desired output of prepared sensitized positive film.

According to this invention the manufacturer of the film, plate or paper will print the pattern design thereon before he ships, 15 and most economically will do this in machines which handle the original large sheets or webs. In printing single coated sensitized positive plates, film or paper the screens may be in the form of opaque or 20 black lines on the surface of solid glass cylinders with the light inside, so as to print continuously, it being seen that the light will pass between the lines and produce a latent image in the emulsion. The material 25 can then be cut up and handled and shipped in the ordinary manner of handling unexposed sensitized photographic materials.

In Figure 2 are shown two glass plates 30 put together face to face with designs displaced, and secured together, to receive images of complementary color families in the unexposed portions 3, 4 being the printed undeveloped design.

In Figure 3 the base 1 is transparent and 35 carries on each side an emulsion 2 printed with lines 4 relatively displaced and having residual sensitive relatively displaced portions 3.

The designs may be of any desired symmetrical pattern such as parallel lines, or 40 checker board, etc., but generally the total area of the printed portions will preferably slightly exceed the total area of the unprinted portions. In the case of double 45 coated plate or film as in Figure 3 for example, the printed lines 4 on one side will be very slightly wider than the underlying imprinted lines 3 by an amount to be determined by experience, and to some extent 50 by the particular chemical process used for applying and fixing the color. The reason for this is that a preferred method of coloring is to bleach and mordant the lines, and I have found by experience that some 55 of these bleaches and mordants, as well as the other treatments necessary in supplying the color, tend to cause the gelatin carrying the bleached portions to appreciably shrink, so that if there is not a slight overlap of the 60 printed portions of the design on each side there might be a separation owing to this shrinkage of the gelatin. If there is too much overlap objectionable lines of black 65 will be produced.

66 The particular manner of photographi-

cally printing the designs on the sensitized material is not material to the invention, as various methods are possible, such as using flat screens instead of rollers, offset printing methods using opaque removable inks or resists, etc. Care must be exercised in printing double coated plate or film to obtain the necessary registration of the designs so as to maintain the proper displacement, but this will not furnish any particular difficulty to the manufacturer, inasmuch as there is no shrinkage of the photographic stock to be taken care of. Where a plurality of displaced designs is embodied in one base, as in Figure 3, for example both designs should preferably be printed at once as by rollers or flat screens held in proper registry by suitable pins. If the designs are once printed subsequent shrinkage due to treatment becomes immaterial because alike on both sides. Where two single coated transparencies are put together by hand, as in Figure 2, very satisfactory registration can be effected by eye; assuming that the designs are alike and of equal or nearly equal total area in printed and unprinted portions.

In the production of colored motion picture films on the additive principle, this invention will furnish a decided advantage by 95 enabling the possessor of color selection negatives to make his positive prints and then to complete the coloring by suitable processes desired.

I have found that for color motion picture work a design composed of 800 parallel lines to the inch is sufficiently fine to blend in transmitted light giving extremely beautiful colors, good perspective and pure whites, but I expressly do not restrict myself to any specific fineness or design.

Where I speak of making the displaced impressions in different strata of emulsion, I intend to include both the species of Figure 3 having the strata on opposite sides of the base, and also a form such as in Figure 1 wherein one design can be printed from the front, and the other in the inner stratum of emulsion through a transparent support.

In both of these forms it will be observed that development and fixing of the latent design images alone will simply produce a single discontinuous black image on the entire support, and that in the finished positive printed from color value images, the latter together constitute but a single discontinuous image. Ultimately in order to view this image, the black design image will be rendered transparent, and toned, but additive color transparencies can be produced from the product of this invention without coloring the images, by a process other than that specifically disclosed in said application #243879.

I also intend to cover in the claims an oppositely coated support such as in Figure 3, having the design in one emulsion, and the other left complete for such further use in 5 making a color transparency as may be desired by the user, as at the present time, there are numerous known ways of producing additive color transparencies other than that specifically shown and claimed in the 10 patent aforesaid. For registration of a plurality of negative images on opposite sides, or the same side, of the same positive area, the registration method shown in my Patent #1,259,411, March 12, 1918, will be 15 satisfactory.

What I claim is:

1. As a article of manufacture, a support carrying sensitive photographic emulsion and having impressed therein a latent image 20 comprising a subdivided additive screen design providing residual sensitive portions.
2. As an article of manufacture, a transparent support carrying sensitive photographic emulsion having impressed in one 25 stratum thereof a latent image comprising a subdivided additive screen design providing residual sensitive portions, and in another stratum a like latent screen image providing like residual sensitive portions, the respective designs and sensitive portions being relatively displaced so that latent image 30 portions in one stratum overlie residual sensitive portions in the other.
3. As an article of manufacture, a transparent support carrying a sensitive photographic emulsion on each side, at least one of said emulsions having impressed therein a latent image comprising a subdivided additive screen design providing residual 35 sensitive portions to subsequently receive an image.
4. As an article of manufacture, a transparent support carrying a sensitive photographic emulsion on each side having impressed in each of said emulsions a latent 40 image comprising a subdivided additive screen design providing residual sensitive

portions, the respective designs and sensitive portions being relatively displaced so that latent image portions in one emulsion overlie residual sensitive portions in the other. 45

5. As an article of manufacture, a support carrying sensitive photographic emulsion having impressed therein a latent image comprising a subdivided additive screen 55 design providing residual sensitive portions, the total area of latent image portions exceeding that of the sensitive portions.

6. As an article of manufacture, a transparent support carrying a sensitive photographic emulsion on each side having impressed in each of said emulsions a latent image comprising a subdivided additive screen design providing residual sensitive 60 portions, the respective designs and sensitive portions being relatively displaced and of such different areas that latent image portions in one emulsion overlie and overlap the residual sensitive portions in the other emulsion. 65

7. As an article of manufacture, a transparent support carrying sensitive emulsion having impressed in different strata thereof latent images providing regularly subdivided residual sensitive portions relatively 70 displaced, the whole when developed producing a discontinuous single black image in transmitted light. 75

8. As an article of manufacture, a transparent film support carrying sensitive emulsion on each side having impressed in each emulsion latent subdivided images leaving intervening sensitive portions for also receiving impressions on each side from color value records, the sensitive portions on one 80 side registering with the latent image portions on the other side, whereby upon development the whole produces a single discontinuous design image and a single discontinuous image from two negatives. 85

Signed at New York in the county of New York and State of New York, this 19th day of March, 1920.

WILLIAM V. D. KELLEY.
